[57] ABSTRACT

A fabric former and method for shaping sleeves and the like from a flat fabric comprises a base and an upright support on the base including a rigid backing member having a rounded top edge with a pad thereon to simulate curvature of the shoulder cap. The pad is marked with indicia for a particular armhole size. The cut fabric also has indicia for a particular armhole size which is first aligned with the indicia on the pad and then pinned in place thereon. Repeated steam-pressing and drying shape the cut fabric of the desired curvature while being held in place on the former.

SET-IN SLEEVE FORMER

This invention in general relates to forms or supports for shaping a flat fabric in the making of parts of garments and more particularly to a novel and improved former and method for use in shaping set-in sleeves and the like prior to sewing them into the garment.

The set-in sleeves of high quality garments have no excess gathers or pleats along the top of the sleeve cap. Of all the types of sleeves found in clothing construction the set-in sleeve presents the greatest problem as to avoiding excess gathers or pleats because the cut fabric of a set-in sleeve measures larger than the armhole. Because of this the sleeve must be eased or carefully fitted in the armhole.

Accordingly, it is an object of this invention to provide a novel and improved former for sleeves and the like on which the cut fabric may be placed to shape it to conform to the curvature of the shoulder and that of a particular armhole size and be formed thereon to accurately fit that armhole prior to sewing it in place.

Another object of this invention is to provide a novel and improved former for set-in sleeves and the like which provides a firm support for the cut fabric during steam-pressing, is self-supporting to maintain the fabric in an upright, readily accessible position and will retain its shape for reuse many times.

A further object of this invention is to provide a former for making set-in sleeves which can be collapsed to a smaller dimension for storing when not in use.

Yet a further object of the present invention is to provide a novel and improved method of easily and efficiently forming the desired curvature in a cut fabric for a particular armhole and a further object is to provide a novel former for use in carrying out the improved method.

In accordance with the present invention there is provided a former comprising a base portion and a shoulder support which is disposed upright for use and pivots to a collapsed position for storage. The shoulder support has a pad along a substantially semicircular top edge and across the front face and is rounded between the top edge and front face to simulate the shape of a shoulder. This padded support provides a firm body for a cut of fabric and it is marked according to the dimension of a particular armhole of the garment. The cut fabric or material for a sleeve has indicia along its curved edge which is aligned with the indicia on the pad and the cut fabric is then pinned in place. The cut fabric is repeatedly steam-pressed and dried on the former until it takes the desired curvature.

Other objects, advantages and capabilities of the present invention will become more apparent as the description proceeds taken in conjunction with the accompanying drawings, in which:

FIG. 1 is a fragmentary perspective view of a garment with a set-in sleeve;

FIG. 2 is a front elevation view of a fabric former embodying features of the present invention;

FIG. 3 is a side elevation view of a fabric former shown in FIG. 2;

FIG. 4 is a rear elevation view of the former shown in FIG. 2;

FIG. 5 is a sectional view taken along lines 5—5 of FIG. 4;

FIG. 6 is an elevation view of a cut fabric with a draw thread sewn along the top edge; and

FIG. 7 is a perspective view of a former having the cut fabric pinned in place for steam-pressing.

Referring now to the drawings, a finished garment with a set-in sleeve is illustrated at 11 in FIG. 1 and as shown the sleeve is curved along the cap portion 11a of the sleeve thereof to conform to the shoulder of the wearer. The usual difficulty with set-in sleeves is that the sleeve cap measures larger than the armhole and must be eased into position to avoid excess gathers or pleats where the sleeve cap joins the armhole portion of the garment.

The fabric former 12 shown for shaping the cut fabric comprises a base 13 and a shoulder form or support 14 pivotally mounted on the base 13 by means of a pair of spaced hinges

15 and 16 fastened to the base and the support so that the support 14 may pivot rearwardly to a collapsed position as represented in dashed lines at 14a and in this collapsed position the support 14 is disposed parallel to the top of base 13. A releasable lock or latch for the support 14 including an eyelet 18 extending through the front face of the support and a hook 19 attached to the top of the base 13 are provided to hold the support 14 in an upright position and firmly in place so that the assembly is self-supporting during the use thereof.

The base 13 is of rectangular shape with flat top and bottom surfaces and straight ends and preferably is made of wood. The shoulder support 14 includes a backing member or shoulder board 21 of a generally rectangular shape and has a straight lower end and a curved semicircular contour at the other end. The semicircular shape is provided to match the configuration of the upper half of the armhole opening. The shoulder board 21 preferably is made of wood. A cap-like cushion or pad 22 is placed across the front face of the backing member 21 and over the top curved edge and is secured to the rear face as with staples 23 which penetrate the backing member 21. This provides a shape characterized by curvature across the top of the support and between the top and front faces to simulate the shape of a shoulder. Pad 22 comprises an outer fabric layer 22a and inner padding 22b. Pad 22 permits the insertion of pins into the former and the backing member or board 21 provides a firm support for the fabric to hold it in place during steam-pressing as described hereinafter.

The cut fabric 25, as best shown in FIG. 6, has a curved upper edge 25a which terminates in a pair of straight side edges 25b and 25c and when folded into the sleeve shape overlap one another to form the sleeve hole. The curved upper edge 25a of the cut fabric has indicia located at the center and on each side represented as arrows at 26, 27 and 28, respectively. A draw thread 29 is shown stitched inwardly along the curved edge 25a to pull the fabric into place on the former as described hereinafter. The pad 22 is marked at the center and on each side with indicia represented as X's 31, 32 and 33, respectively.

In the use of the former 12, the cut fabric 25 is placed on the padded upright support 14 with the curved upper surface 25a being disposed along the forward face of the semicircular top end and the draw thread 29 is pulled from both directions until the indicia on the pad matches the indicia on the cut sleeve fabric. Only they line up, the cut fabric 25 is then pinned into place on the pad by pins 35. A steam iron, not shown, is then used to steam-press the sleeve fabric into shape. The steam-pressing and drying is repeated until the fabric is smooth and conforms to the former. The shaped sleeve is then removed from the former and stitched to the garment at the armhole so that the finished set-in sleeve will take the appearance of that shown in FIG. 1.

From the foregoing it is apparent that the advantage of hinging the shoulder board to the base is that it permits it to be set for use in an upright position and when not in use can be collapsed. The pad on a rigid board backing has the advantage of providing a firm support into which pins may be inserted and the combined base and upright board is self-supporting to maintain the cut fabric in an upright position which is handy to work on.

Although the present invention has been described with a certain degree of particularity, it is understood that the present disclosure has been made by way of example and that changes in details of structure and method may be made without departing from the spirit thereof.

What is claimed is:

1. A fabric former for shaping the cap portion of a sleeve adapted to be sewn along the armhole and the like comprising a rigid base and a rigid shoulder board pivotally mounted on the base to move from an upright position to a horizontal collapsed position, said shoulder board having substantially flat front and rear faces and flat sides with a semi-circular shaped top edge curved convexly across its width and having the junc-

ture between the front face and top edge rounded along the top edge to simulate the curvature of the cap portion of a shoulder, a cap-like pad mounted on said top edge and extending across the front face of the shoulder board, said pad being secured to the shoulder board along the rear face of the shoulder board, said pad including an outer fabric layer and an inner resilient filler layer, said top edge and pad having indicia

corresponding to the dimension of a particular armhole and sized to match up the upper cap portion of the sleeve with the upper half of the armhole and support a cut material pinned to the pad, and a releasable lock to hold the shoulder board in an upright position on said base.
